UNITED STATES PATENT OFFICE

2,552,919

PLUG BUTTON, CLOSURE, AND THE LIKE

Philip D. Becker, Hingham, Mass., assignor to
United-Carr Fastener Corporation, Cambridge,
Mass., a corporation of Massachusetts

Application November 17, 1948, Serial No. 60,500

4 Claims. (Cl. 220—60)

1

The present invention relates to plug buttons and the like adapted for attachment to apertured supports, and aims generally to improve existing devices of that type.

More particularly, the invention relates to that type of plug button closure and the like shown and described in my copending application Serial No. 60,497, filed Nov. 17, 1948, and Serial No. 60,498, filed Nov. 17, 1948, in which the attaching member of the plug button or closure comprises an axially spaced support-engaging fastener-supporting annulus and a cap-supporting rim.

A primary object of the present invention is the provision of an improved cap member for attachment to the cap-supporting rim of the attaching member, which rim advantageously comprises a circular series of circumferentially spaced flanged sections.

A further object of the invention is the provision of an improved cap structure which may be crimped or clenched to a multiple-part annular rim while resisting radial inward movement of the rim sections during the capping operation.

Other aims and objects of the invention will be apparent to persons skilled in the art to which the invention relates from a consideration of the accompanying drawings and annexed specification illustrating and describing a preferred embodiment of the invention.

In the drawings:

Fig. 1 is a top plan view of a plug button as applied to an apertured support;

Fig. 2 is a side elevation thereof;

Fig. 3 is a plan view of a portion of a blank 35 suitable for forming an attaching member for the plug button or closure;

Fig. 4 is a detail transverse sectional view of the plug button or closure as taken on the line 4—4 of Fig. 1;

Fig. 5 is a detail transverse sectional view of the plug button or closure as taken on the line 5—5 of Fig. 1;

Fig. 6 is a plan view of a portion of another form of blank suitable for forming the attaching member of the plug button or closure and the like;

Fig. 7 is an enlarged transverse sectional view illustrating the first step of applying a cap member to the attaching member shown in Fig. 6; and

Fig. 8 is a transverse sectional view illustrating the completed cap-attaching member.

Referring to the drawings, the plug button, closure or the like is preferably of two-part construction comprising an attaching member 10 and a cap member 15.

2

The attaching member 10 may be of any suitable construction, preferably of the type disclosed in my two copending applications aforesaid, and advantageously comprises an inner annulus or ring member 11 supporting a circular series of circumferentially spaced support-engaging fastener members 12 extending divergently toward an axially spaced cap-supporting rim, the latter comprising a circular series of segments 13, each connected to the annulus or ring member 11 by a connecting strut 14. This type of attaching member 10 is more fully disclosed in my copending applications aforesaid, and reference is made thereto for a more complete illustration and description of the construction of that member. It will be understood that said circular series of segments 13 collectively make up the cap-supporting rim. The segments 13 are movable radially inwardly when pressure is applied circumferentially being connected to the annulus 11 by the struts 14.

The cap 15 may be of any suitable construction, such for example as an annular ring member or a continuous closure for the cap-supporting rim, depending upon the use and nature of the installation in which the plug button is used, as is well understood in the art.

Referring to the embodiment of the invention shown in Figs. 3 to 5 inclusive, the cap-supporting rim is composed of circumferentially spaced segments 13 bent at an angle to the divergent struts 14 and generally disposed in a common horizontal plane. The segments 13 may be of any desired length, depending largely upon the desired width and shape of the intervening support-engaging fastener member 12 and may be of such length that adjacent ends of adjoining segments will be spaced apart. In such a construction the segments 13 and struts 14 will be radially inwardly movable as the struts are flexed about their connection with the annular rim 11.

The cap 15 preferably comprises a continuous annular rim 21 provided with an angularly extending annular bead 22 inwardly of the peripheral edge of the rim and of a diameter equal to the diameter between opposed struts 14 of the finished plug button. The bead 22 provides an angular shoulder or abutment for the struts 14 to limit or restrain radial inward movement of the struts as the outer marginal edge portion of the rim 21 is folded or crimped around the segments 13.

In Figs. 7 and 8 there is illustrated a modified form of the invention in which the segments 33 are of inverted U- or V-shape and are adapted to collectively provide a cap-supporting rim.

The cap 40 is preferably pre-shaped to provide a deep marginal flange 41 outwardly of a peripheral annular groove 42 adapted to receive the reversely flanged segments 33, the inner circumferential wall 44 of the groove 42 providing an abutment to restrain radial inward movement of the struts 34 as the marginal edge or rim of the flange 41 is folded or crimped around the flanged segments 33, as shown in Fig. 8.

As will be apparent to persons skilled in the art, the invention permits the initial shaping of the attaching member to a predetermined diameter and the ready application of the cap member to the cap-supporting rim thereof which may be composed of radially resilient and movable sections.

Although I have illustrated and described preferred forms of the invention, I do not intend to be restricted thereto as the scope of the invention is best defined in the appended claims.

I claim:

1. A plug button or like closure for attachment to an apertured support comprising an attaching member having an annular fastener supporting rim, a plurality of resilient fastener members extending obliquely from said rim, a circular series of circumferentially spaced radial arms extending outwardly from and obliquely to said rim, the outer terminal ends of the arms being flanged to provide cap-supporting surfaces, a closure cap provided with an annular embossment inwardly of its peripheral edge adapted to fit and engage a portion of the inner faces of said obliquely disposed arms to restrain said arms from inward radial movement, and said cap having a rim portion outwardly of said embossment foldable over said arm flanges to secure the cap in assembly with said attaching member.

2. A plug button or like closure for attachment to an apertured support comprising an attaching member having an annular fastener supporting rim, a plurality of resilient fastener members extending obliquely from said rim, a circular series of circumferentially spaced radial arms extending outwardly from and obliquely to said rim, the outer terminal ends of the arms being flanged to provide cap-supporting surfaces, a closure cap provided with an annular bead adapted to be positioned within said circular series of arms to restrain inward radial movement thereof, and an

annular rim surrounding said bead foldable over said arm flanges to secure the cap in assembly with said attaching member.

3. A plug button or like closure for attachment to an apertured support comprising an attaching member having an annular fastener supporting rim, a plurality of resilient fastener members extending obliquely from said rim, a circular series of circumferentially spaced radial arms extending outwardly from and obliquely to said rim, the outer terminal ends of the arms being reversely flanged to provide collectively a cap-supporting rim, a closure cap provided with peripheral grooves adapted to receive and embrace said cap-supporting rim and to restrain said arms from inward radial movement, an outer peripheral portion of said groove being bindable around said rim to secure the cap in assembly with the attaching member.

20 4. A plug button or like closure for attachment to an apertured support comprising an attaching member having an annular fastener-supporting rim, a plurality of resilient fastener members extending obliquely from said rim, a circular series 25 of circumferentially spaced arms extending angularly outward from said rim, the outer terminal ends of the arms being flanged to provide cap-supporting surfaces, a closure cap provided with an annular shoulder adapted to fit and engage portions of the inner faces of said angularly disposed arms to restrain inward radial movement thereof, said closure cap having an annular rim outwardly of said shoulder and foldable over said arm flanges to secure the cap in assembly 35 with said attaching member.
